UNITED STATES PATENT OFFICE.

JEFFERSON B. DYER AND JAMES D. HOBBS, OF HANSON, OKLAHOMA.

CHURN.

1,015,383.

Specification of Letters Patent.

Patented Jan. 23, 1912.

Application filed October 7, 1911. Serial No. 653,309.

To all whom it may concern:

Be it known that we, JEFFERSON B. DYER and JAMES D. HOBBS, citizens of the United States, residing at Hanson, in the county of Sequoyah and State of Oklahoma, have invented certain new and useful Improvements in Churns, of which the following is a specification, reference being had to the accompanying drawings.

10 This invention relates to certain new and useful improvements in churns and has for its object to provide a simple, durable and efficient device of this character wherein the churn vat or receptacle is vertically reciprocated so as to thoroughly agitate the contents thereof and induce the rapid formation of butter.

A further object of the invention resides in the provision of improved means for 20 mounting the churn vat or body in a suitable supporting frame, said mounting including means for rigidly securing the top or cover upon the churn, and means for connecting the operating mechanism to the carrier frame of the churn whereby churns of various sizes may be employed.

With the above and other objects in view, the invention consists of the novel features of construction, combination and arrangement of parts hereinafter fully described and claimed, and illustrated in the accompanying drawings, in which—

Figure 1 is a side elevation of a churn embodying our improvements; Fig. 2 is a 35 top plan view; and Fig. 3 is an enlarged detail longitudinal section through one of the adjustable sleeves for connecting the operating pitman to the carrier plane of the churn.

40 Referring in detail to the drawing 5 designates the main frame which consists of the vertical uprights 6 which are rigidly mounted at their lower ends upon a suitable base 7. The upper ends of the uprights 6 are offset as shown at 8 and are braced by means of the horizontal connecting bars 9 and the diagonal bars 10. A horizontal bar 11 is also arranged between the uprights at their lower ends in spaced relation to the base 7. A central vertical bar or upright 12 is also arranged between the base 7 and the upper horizontal frame bar 9. Upon the top of this frame structure and centrally thereon a transverse shaft 13 is mounted in a suitable bearing and to one end of this shaft a fly or

balance wheel 14 is fixed while to the other end thereof a pinion 15 is secured. An operating gear wheel 16 is also mounted upon the upper end of the frame structure and meshes with the teeth of the pinion 15. 60 This gear is provided with a crank handle 17 whereby the same may be turned in the operation of the machine.

The churn body or vat C is mounted in a suitable frame which consists of the parallel vertical rods 18 which are movably disposed through openings provided in the lower horizontal bar 11 of the main frame and in the upper bar 9 thereof. The churn vat C is removably mounted upon a platform or 70 base 20 to opposite sides of which the laterally extending rods 21 are secured, said rods being fixed to the vertical frame rods 18. An adjustable cross rod 22 connects the rods 18 and is provided at its ends with the 75 sleeves 23 which carry set screws 24 for binding engagement with the rods 18 whereby the cross rod 22 may be rigidly secured in its adjusted position. A clamping screw 25 is threaded centrally through the cross 80 rod 22 which is provided with a flattened portion therein and is adapted for clamping engagement with the cover or top T of the churn vat to securely hold the same in position during the reciprocation of the churn. Sleeves 26 are longitudinally adjustable 85 upon the cross rod 22 and carry suitable set screws 27 to secure said sleeves thereon. Link rods 28 are pivotally connected to the inner ends of these sleeves and are loosely 90 connected to the lower end of a pitman rod 29 which is eccentrically connected as indicated at 30 to the fly wheel 14. It will thus be seen that by loosening the set screws 27 and 24, the rod 22 may be vertically adjusted 95 upon the frame rods 18 so as to permit a churn vat or receptacle of any desired capacity to be mounted in the reciprocal frame. It will also be appreciated that by simply loosening the screws 24, the top T of the 100 churn body will be loosened and removed by the upward movement of the bar 22, the reciprocating frame in which said churn body is mounted resting upon the lower transverse bar 11 of the main frame. The churn body 105 may thus be very quickly removed without requiring the manipulation of the clamping screw 25.

The operation of the device is substantially as follows. After the milk and cream 110

have been placed within the churn vat and the same arranged upon the base 20, the screw 25 is properly adjusted to rigidly retain the top upon said vat. After tightening the set screws 24 and 27 the churn will be very rigidly held in position in its frame and the operator then grasps the crank handle 17 and by turning the gear 16 imparts a reciprocatory movement to said frame through the medium of the pitman rod 29 and the link rods 28 which connect the fly wheel 14 therewith. In this movement of the frame, the rods 18 thereof slide freely through the openings in the main frame bars 9 and 11. It will be readily observed that in this manner a very rapid reciprocatory movement may be imparted to the churn so that the contents thereof are very thoroughly agitated thus reducing to a minimum the time necessary to the production of the butter and correspondingly decreasing the manual labor. It will also be seen that the churn vat may be easily and quickly removed and another substituted therefor without undue loss of time.

The various parts are extremely simple and the cost of manufacture will be correspondingly small. The device is also highly durable and very efficient in practical use.

While we have shown and described the preferred construction and arrangement of the various parts, it will be obvious that the invention is susceptible of a great many minor modifications in the form and proportion thereof without departing from the

essential feature or sacrificing any of the advantages of the invention.

Having thus described the invention what is claimed is:—

The combination with a churn body, of a fixed main frame, a vertical reciprocatory frame mounted within the main frame comprising spaced parallel side rods, a platform rigidly arranged between the side rods at their lower ends on which the churn body is supported, a cross bar vertically adjustable upon the upper end portions of said rods, a cover clamping screw carried by the cross rod, operating means mounted in the main frame including a fly wheel, a pitman eccentrically connected at one end to said fly wheel, sleeves longitudinally adjustable on said cross rod, and link rods pivotally connected to said sleeves and loosely connected to said pitman, substantially as and for the purpose specified.

In testimony whereof we hereunto affix our signatures in the presence of two witnesses.
